UNITED STATES PATENT OFFICE.

RAYMOND H. KILLINGER, OF PORTLAND, MAINE.

OIL CUP.

Application filed February 21, 1923. Serial No. 620,474.

To all whom it may concern:

Be it known that I, RAYMOND H. KILLINGER, a citizen of the United States, residing at Portland, in the county of Cumberland 5 and State of Maine, have invented certain new and useful Improvements in Oil Cups, of which the following is a specification.

The present invention relates to oil cups and is especially adapted for use on air 10 pumps of locomotive air compressors.

An object of the invention is to mount an oil cup on the air end of a locomotive air compressor pump which automatically functions, by the normal operation of the pump, 15 to constantly and adequately lubricate the latter to thereby eliminate breaking or otherwise incapacitating the air end of the piston due to insufficient lubrication.

A further object of this invention is to 20 provide a lubricator for the air end of pumps which eliminates the possibility of feeding the oil in excess quantities thereby preventing sluggish operation of the mechanism caused by the accumulation of oil especially when the latter attains a viscous 25 consistency.

Co-ordinate objects of the invention will be apparent from the following description 30 of the present preferred form of the invention taken in connection with the accompanying drawings wherein:—

Fig. 1 is a fragmentary sectional view 35 of an air pump used with locomotive air compressors illustrating the application of my improved oil cup thereon; and

Fig. 2 is a longitudinal sectional view of the oil cup per se showing the top plug removed.

In order to illustrate the application of 40 this invention a portion of an air pump, as used on locomotive air compressors, 3 is shown which may be of the usual or any other configuration. The upper part of the pump is formed to provide the steam end 45 and the lower part 5 comprises the air end of the pump in a well known manner. In the present instance the top 6 of the air end of the pump is provided with an opening 7 which communicates with the air end of the 50 pump and is provided at its upper end with screwthreads 8.

My improved oil cup consists of a body 9 shown in the present instance to be of cylindrical configuration and equipped adjacent 55 its lower end with an integral partition 10. The inner periphery of the lower end of the

body 9 is provided with screwthreads 11 while the inner periphery of the upper end of the body is provided with screwthreads 12. A recess is formed in the inner periphery of the body directly below the screwthreads 12 in which a washer 13 is mounted the upper face of which projects above the lower end of the screwthreads 12 so as to be impinged by the inner end of a cap 14 which is detachably engaged with the threaded upper end of the body. The cap 14 is provided with a central screwthreaded opening 15 serving as a filler opening which is normally closed by a plug 16. 60 The screwthreads 11 are engaged by corresponding threads formed on a bottom cap 17 the latter having a well 18 formed therein which communicates with a central outlet opening. The central outlet opening is 65 screwthreaded and engaged by corresponding threads formed on one end of an outlet pipe 19, the opposite end of the latter being engaged with the threads 8 of the pump opening 7. 70

The partition 10 and washer 13 are provided with central aligning openings through which the opposite ends of a spindle 20 are slidably mounted. The lower end of the spindle extends appreciably below the 75 bottom face of the partition 10 and is provided with screwthreads 21 upon which an abutment 22 and nut 23 are mounted. The inner face of the abutment 22 is centrally recessed to provide a fount 24 into which the 80 lubricant is permitted to gravitate through openings 25 formed in the partition 10. The bottom face of the abutment is dished out as indicated by the numeral 26 to provide a pocket adapted for the reception of 85 air in a manner hereinafter set forth.

In order to close communication through the openings 25 a suitable valve 26' is provided which is formed integral with the spindle 20, adjacent the lower end of the 90 latter but above the partition 10. This valve 26' is provided with a recess 27 which surrounds the lower end of the spindle 20 and is so formed that the wall thereof rises just outside of the openings 25. The lower end 95 of the valve 26' is normally held in snug engagement with the upper face of the partition 10 by means of a spring 28. The spring 28 is convoluted on the spindle 20 and has one end thereof engaged with the lower face 100 of the washer 13 and the opposite end engaged with the upper end of the valve 26'. 105

To fill the oil cup the plug 16 is removed and oil introduced through the filler opening 15 and permitted to pass downwardly through openings 29 formed in the washer 5 13. On the compression stroke of the pump, air passes upwardly through the pipe 19 and into the pocket 26 of the abutment 22 so as to force the latter against the lower face of the partition 10 against the resistance of the 10 spring 28. This elevates the valve 26' so as to permit the passage of oil therebeneath through the openings 25 and into the fount 24. On the suction stroke of the pump the 15 lubricator is sucked from the fount 24 over the top of the abutment 22 and into the air end of the pump in an apparent manner. The peculiar formation of valve positively prevents the lubricator in the oil cup body from being withdrawn from the latter. 20 Moreover, the construction of the abutment prevents air from entering the oil cup body. The abutment may be adjusted to the desired position and secured from displacement by the nut 21, which latter may be secured 25 from any movement on the spindle by bifurcating the lower end of the latter as indicated at 30.

It is of course to be understood that various changes may be made in this device 30 especially in the details of construction, proportion and arrangement of parts. The essence of this invention, however, is to provide a lubricator cup which is engageable with the air end of a pump of the character 35 herein described so as to automatically function by the normal operation of the pump thereby constantly lubricating the pump with a predetermined volume of oil. The construction herein recited will be found, 40 however, to produce effective results since actual tests have demonstrated that a pump running continuously for ninety-six hours.

will use only a gill of lubricant. Applicant, therefore, reserves the right to make such changes in the device as come within the 45 purview of the claims appended hereto.

What is claimed is:—

1. An oil cup including a body equipped with a partition in its lower end and a washer at its upper end both of which are provided with lubricant openings, a spindle movably mounted in said partition and washer and equipped with a valve engageable over the openings in said partition to normally close communication through the latter, an abutment mounted on the lower end of said spindle the upper face of which is recessed to provide an oil fount the lower face being formed to provide an air pocket, and a pipe engageable in the lower end of 60 said body to direct an air blast into the pocket of said abutment for disengaging the valve, withdrawal of air through said pipe causing the oil in the abutment fount to be sucked through the pipe. 65

2. A lubricator for the pumps of air compressors including a receptacle provided with an outlet opening, a valve movably mounted in said receptacle and normally closing communication through said opening, means in operative connection with said valve to be impinged by air upon the compression stroke of the pump to unseat said valve and urge said means into engagement with the receptacle for closing communication through said opening, said means being provided with a recess to receive a predetermined quantity of oil passing through said opening when said valve is unseated, the suction stroke of the pump releasing said 80 means to permit said valve to close and to withdraw the lubricant from the recess of said means. 75

RAYMOND H. KILLINGER.
